CLAIM

The ornamental design for a bear storage bin, as shown and described.

DESCRIPTION

FIG. 1 is a front perspective view of a bear storage bin, showing my new design;

FIG. 2 is a front elevation view thereof;

FIG. 3 is a rear elevation view thereof;

FIG. 4 is a left elevation view thereof, with the right elevation view being a mirror image and therefore not shown;

FIG. 5 is a top plan view thereof;

FIG. 6 is a bottom plan view thereof; and,

FIG. 7 is an exploded perspective view thereof.

The broken lines shown in the drawings form no part of the claimed design.

1 Claim, 4 Drawing Sheets
